Ernest J. Francis, Harrisonburg, Va.

Application January 23, 1952, Serial No. 18,183

Term of patent 14 years

(Cl. D58—12)

To all whom it may concern:

Be it known that I, Ernest J. Francis, a citizen of the United States and a resident of the city of Harrisonburg, State of Virginia, have invented a new, original, and ornamental Design for a Box, of which the following is a specification, reference being had to the accompanying drawing, forming a part hereof.

I claim:

The ornamental design for a box, as shown.
ERNEST J. FRANCIS.
